UNITED STATES PATENT OFFICE.

JACOB M. GOUGH AND JOHN SPEAKMAN, OF NEW CASTLE, AND NATHAN F. CANADAY, OF HAGERSTOWN, INDIANA.

COMBINED SCHOOL-DESK AND SEAT.

SPECIFICATION forming part of Letters Patent No. 367,037, dated July 26, 1857.

Application filed December 24, 1886. Serial No. 222,483. (No model.)

To all whom it may concern:

Be it known that we, JACOB M. GOUGH, JOHN SPEAKMAN, and NATHAN F. CANADAY, of New Castle and Hagerstown, in the counties 5 of Henry and Wayne, respectively, and State of Indiana, have invented certain new and useful Improvements in Combined School-Desks and Seats; and we do hereby declare the following to be a full, clear, and exact description 10 of the invention, such as will enable others skilled in the art to which it appertains to make and use the same.

Our invention relates to an improvement in school-desks and seats, and more particularly 15 to a style of combined seat and desk in which the desk is supported upon a vertical column or standard and the seat connected thereto in a manner to permit its vertical and lateral adjustment.

20 The object of our present invention is to further perfect and render more practical certain details in the patent issued to Jesse M. Lamb, dated November 16, 1886, numbered 352,762, in which a vertical column is made to support 25 a desk upon its top section, the upper portion of the column telescoping or sliding within a tubular lower part, the lower portion of this vertically-adjustable column having a set-screw in its side wall that engages with the 30 upper piece of the column, and is intended to hold it in secured or rigid adjustment with regard to its hollow lower support. We have found it desirable to have the seat as an entirety—that is, the seat and its back-board or 35 shoulder-support made together—as an integral feature, and as such combined with the vertical column of a desk, and be either wholly or partially sustained by this column with a free lateral movement and means for vertical 40 adjustment either on the seat-standard or the desk-supporting column. Further, it has in practice been found to be of great advantage to construct the desk-support or upper portion of the column so that this desk-support may 45 have a firm shoulder or collar upon which to revolve, as on a base, and that this collar that thus supports the desk in its vertically-adjusted position may be elevated or depressed and secured at any desired point on the column 50 on which it slides, the desk being secured

from rotative movement by a thumb screw that will hold the desk in any position of adjustment in a predetermined horizontal plane. The advantages pertaining to these improved features of our invention are manifest, as the 55 means provided for independent adjustment of the desk vertically and laterally and a separate adjustment of a seat having its back attached to or integral with this seat will permit a desk and its seat to be changed in any 60 direction to receive light from the rear or front or at any angle laterally, each seat and its complementary desk being combined together for use independent of the assigned position of any other desk or seat or combined desks and 65 seats, and without interference with other seats of a series.

We have further made provision in our improvement for the attachment of the bracket seat-support to the main column in a manner 70 to prevent it from interference with the ingress of pupils of either sex.

With these ends in view our invention consists in certain features of construction and combinations of parts, that will be hereinafter 75 described, and pointed out in the claims.

In the drawings making a part of this specification, Figure 1 is a side elevation of the combined desk and seat. Fig. 2 is a side elevation of a modified form of the desk and seat 80 combined. Fig. 3 is a plan view of the combination of desk and seat shown in Fig. 1. Fig. 4 is a plan view of the modification shown in Fig. 2. Figs. 5 and 6 are views of a swivel-coupler as applied to the seat. 85

C is a desk of preferred rectangular form. The vertical column A (see Figs. 1 and 2) is provided with an enlarged base that extends to form a disk or foot of sufficient diameter to insure stability, this base-flange being perforated at several points in its surface to permit the insertion of screws to affix the column to the floor where it is intended to locate the desk. 90

The piece a is perforated to form a tubular 95 section or sleeve that fits neatly upon the column A, upon which it is designed to be secured. The upper end of the sleeve a terminates in a flange that is firmly attached to the under side of the desk. The sleeve a is true 100

upon its lower end, and rests upon the collar *b*, which encircles the column *A*, and upon which it can be moved vertically, a set-screw being provided to secure it at any desired point, and it will be noticed that a winged thumb-screw, *c*, is inserted in the wall of the sleeve *a* to hold it from rotation on the base-collar *b*, the sleeve being free to turn around on its support *b* when the thumb-screw *c* is released from bearing contact on the column *A*. The position given the desk *C* on the column is shown in Fig. 3, the securing-flange on the sleeve *a* being located at one of the side edges of the desk.

15 Upon the column *A*, near the base-flange *g*, a shoulder or offset is formed to support the ring or collar *i*, which is formed upon the end of the curved connecting-bar *G*, as shown in Fig. 1. The bar *G* is extended laterally a proper distance to provide room between the desk and its attached seat, and at its free end a spider is formed by the junction of two short curved legs, *g*, that with the attached portion of the bar *G* forms a tripod base, upon which the 25 chair or seat *E* is mounted. The manner of supporting the seat *E* on its base is shown in Figs. 1 and 5, a vertical cylindrical shaft, *F*, being formed integral with three supporting-legs, *g*. On this shaft *F* a sleeve, *H*, is placed, which 30 is secured to a flange, or preferably a four-armed spider, (shown at *I* in Fig. 3,) this spider being secured to the under side of the seat *E*. The lower end of the sleeve *H* is provided with a boss or squared teat, *o*. (See Fig. 5.) 25 A box or recessed collar, *O*, is notched in its top surface at *o'* to receive the projecting lug *o* and allow it to enter the recessed groove made in this collar *O*. The channel or groove *o* in the collar *O* will retain the sleeve *H* from 40 being vertically displaced, and yet permit a free rotation of the seat in a horizontal plane. A set-screw, *o'*, is inserted in the collar *O* to secure it in any desired position vertically, to accommodate pupils of varying stature, and 45 thus afford a comfortable seat to youths or adults. A collar, *d*, (see Fig. 1,) is placed above the arm *G* to hold this arm in place and permit it to swing on the column *A*.

It is evident from the foregoing description 50 that the seat and its connected desk, considered together, are complete and independent from any other seat or desk, and that the desk can be adjusted lower or higher to correspond to a given height of seat, the seat being similarly adjustable; and, further, the combined desk and seat can be rotated, each on its own pedestal, and an adjustment of the seat *E* by swinging it around the vertical column *A*, where its connecting-bar *G* is secured, will 55 allow the seat and desk to be made to assume proper relative positions at any determined point with regard to the reflection of the light. This arrangement of the seat with the desk is also shown in Fig. 2, which is a modification 60 of the device shown in Fig. 1.

In Fig. 2 the seat is not made to rotate upon its support, but is connected to a bent arm, *d'*, that is affixed to the seat by a spider-bracket that has its arms riveted to the frame of this seat, as shown in Fig. 4. The arm *d'* 75 has a sleeve, *d*, formed integral with it, which rests upon the collar *e*, both being placed upon the vertical column *A*, that holds the desk *C* in position. This method of construction permits a vertical adjustment of the combined 75 supporting-arm *d'* and seat *E*, by means of the collar *e*, that has a set-screw, *e'*, to secure it in rigid connection with the column *A*.

The desks shown in Figs. 1 and 2 are placed upon their supporting-columns *A* at one of 80 their side edges, as shown in the plan views given in Figs. 3 and 4. This provision is made to permit easy access to the seat and remove the arms *G* or *d'* away from a central position with regard to the desk, where it 85 would be an obstruction to the occupant of such a desk or seat.

The seat and its back are preferably made of two bent pieces of angle-iron that form the edge frame. These pieces are perforated with 90 a series of spaced holes to permit transverse wood strips to be secured upon the pieces *S*, and thus form a cheap and durable seat that from its form will properly support the back and shoulders of an occupant of such a seat. 95

Having fully described our invention, what we claim as new, and desire to secure by Letters Patent, is—

1. The combination, with a standard and a vertically-adjustable desk mounted thereon, 100 of an arm journaled to the standard and projecting outwardly beyond the desk and provided at its free end with feet or supports adapted to rest on the floor, a standard secured to said arm, near the free end thereof, 105 and a seat secured to said latter standard, the said seat being located a sufficient distance from the desk-supporting standard to give free access to it from the seat, substantially as set forth.

2. The combination, with a desk-supporting standard and a seat having a rigid back, 110 of a sleeve secured to the seat, a seat-supporting standard adapted to enter the sleeve, a recessed collar for locking the sleeve on the 115 standard in any desired adjustment, and an arm connecting the seat-supporting standard with the desk-supporting standard, substantially as set forth.

In testimony whereof we have signed this 120 specification in the presence of two subscribing witnesses.

JACOB M. GOUGH.
JOHN SPEAKMAN.
NATHAN F. CANADAY.
